UNITED STATES PATENT OFFICE.

HENRY L. SMITH, OF WATERBURY, CONNECTICUT, ASSIGNOR TO THE E. J. MANVILLE MACHINE COMPANY, OF WATERBURY, CONNECTICUT, A CORPORATION OF CONNECTICUT.

LEAD MECHANISM FOR WOOD-SCREW MACHINES.

1,170,694.

Specification of Letters Patent.

Patented Feb. 8, 1916.

Application filed September 17, 1915. Serial No. 51,174.

To all whom it may concern:

Be it known that I, HENRY L. SMITH, a citizen of the United States, residing at Waterbury, in the county of New Haven 5 and State of Connecticut, have invented a new and useful Improvement in Lead Mechanism for Wood-Screw Machines, of which the following is a specification.

In automatic wood-screw machines the 10 threading tool is fed back and forth for cutting the threads on the blanks, and for the purpose of advancing the tool at the required rate a lead cam, which operates in consonance with the other mechanisms, 15 is provided. As the machines are designed to make screws of different diameters and different lengths it is necessary, in order to have the pitches of the threads correct and to obtain efficiency in operation, to 20 change the lead cam for the various changes in sizes of the screws to be produced.

This invention relates to the mechanism which imparts the feed to the threading tool in machines of this character.

The object of the invention is to so arrange the lead mechanism that the feed cam can be quickly changed without interfering with or disturbing the relations of the intermeshing gears which drive the several mechanisms of the machine in synchronism. In attaining this end the lead cam shaft is made in sections which are detachably fastened together so that they will 25 rotate as one part. One section of the shaft is permanently mounted in the machine and has secured to it a driving gear and a transmission pinion, and the other section of the shaft is removably mounted in the machine and carries the lead cam. When 30 the means which holds the shaft sections together is unfastened the cam part of the shaft can be withdrawn and the lead cam removed and another substituted without disturbing the gear part of the shaft, and 35 thus without interfering with the gears or changing their intermeshing relations.

In the accompanying drawings only so much of an automatic wood-screw machine of a common type is shown as is necessary to 40 illustrate the invention.

Figure 1 shows a side elevation looking at the gear end of such a machine. Fig. 2 shows a front elevation of the gear end of the machine. Fig. 3 is a section on the 45 dotted line 3—3 on Fig. 1. Fig. 4 shows the

ends of the lead shaft sections which interlock.

In the class of machines illustrated the driving power is usually applied to the pulley 1 that is mounted upon the spindle 2 which carries the jaws 3 that hold the blanks while they are being threaded. On the end of the spindle opposite the jaws is a pinion 4 which meshes with an idler 5 that is in mesh with a gear 6. Connected to this latter gear is a pinion 7 which meshes with a gear 8 that is keyed to the hub 9 of a pinion 10. This pinion is in mesh with an idler 11 that is in mesh with a gear 12 connected with a pinion 13 that meshes with a gear 14. 60 All of these gears are usually inclosed in a protecting casing 15 that is fastened to the gear end of the machine.

The pinion 10, on the hub of which the driving gear 8 is mounted, is keyed to the 65 lead shaft and is employed as a transmission pinion for imparting motion to the following gears and pinions of the train. The outer section 16 of the lead shaft is permanently held in bushings 17 and 18. This section of 70 the lead shaft has a longitudinal opening and on its inner end has a transverse tongue 19 and a centering hub 20. The inner section 21 of the lead shaft at its outer end has a circular socket 22 for the centering hub 20 75 and transverse mortise 23 for the tongue 19. A screw bolt 24 is turned from the outside 80 through the central opening in the section 16 into a threaded bore in the end of the section 21 to hold the parts locked together. 85 The lead cam 25 may be fastened to the shaft section 21 by a key 26 and set-screw 27 in the common manner. The lead cam operates 90 against the end of the threading tool shaft 28 for the purpose of imparting the proper 95 lead to the tool.

When, for any purpose, it is desired to change the lead cam the screw bolt 24 is turned out and then the shaft section 21 is withdrawn longitudinally until the lead cam 100 can be removed and another substituted, after which the shaft section 21 is pushed back and engaged with the section 16. As there is no force exerted longitudinally, tending to separate the shaft sections, a 105 relatively small screw bolt may be employed for holding them together. The rotary motion imparted by the driving gears to the outer section is transmitted to the inner section of the lead cam shaft by the interlock- 110

ing of the tongue on one section with the mortise on the other. With this construction when the lead cam is changed the section of the lead cam shaft which bears the gears is not disturbed in any manner, and consequently the relations of the gears always remains the same.

The invention claimed is:

1. In a wood-screw machine the combination of a sectional lead cam shaft, one section of said shaft being movable longitudinally with relation to the other section, means detachably connecting the shaft sections, a lead cam removably mounted on the longitudinally movable section of the shaft, and a driving gear mounted on the other section of the shaft.
2. In a wood-screw machine the combination, of a sectional lead cam shaft, one section being permanently mounted in the machine, and the other section being removably mounted in the machine, a driving gear mounted on the former section and a lead cam mounted on the latter section.
3. The combination in a wood-screw machine, of a sectional shaft, one section being movable longitudinally with relation to the other section, means detachably interlocking the adjacent ends of the shaft sections, 30 means for normally holding the adjacent

ends of the sections of the shaft interlocked, a driving gear mounted on one section of the shaft, and a lead cam removably mounted on the other section of the shaft.

4. The combination in a wood-screw machine, of a train of intermeshing operating gears, a longitudinally separable shaft with one section permanently connected with and rotated by said gears, and a lead cam removably mounted on and rotating with the other section of said shaft.

5. The combination in a wood-screw machine, of a sectional shaft, one section being permanently mounted in the machine and the other section being removably mounted in the machine, an interlocking tongue and mortise on the adjacent ends of the shaft sections, a screw for holding the tongue and mortise in engagement, a driving gear mounted on one shaft section and a lead cam mounted on the other shaft section.

6. The combination in a wood-screw machine of a normally connected sectional shaft, one section being longitudinally fixed and the other section being longitudinally movable, a driving gear permanently held on said longitudinally fixed section, and a lead cam removably fastened on said longitudinally movable section of the shaft.

HENRY L. SMITH.
